STARTER FOR POOL-TYPE TUBES

John M. Cage, Schenectady, N. Y., assignor to
General Electric Company, a corporation of
New York

Application May 11, 1935, Serial No. 20,964

5 Claims. (Cl. 250—27.5)

My invention relates to pool-type tubes in which an arc discharge is controlled by a starting electrode projecting below the surface of the pool. More particularly, my invention provides 5 a starting electrode of such configuration that the potential required to initiate the arc discharge is rendered substantially independent of variations in the pool level.

For many of the applications in which controlled mercury pool tubes are used, it is of 10 extreme importance that starting shall occur at a definite potential point with respect to each cycle of the alternating input voltage. As a practical matter, however, a number of factors tend 15 to prevent the attainment of this desired constancy. It is well known, for example, that variations in the level of the mercury pool produced either by external vibrations or by the conditions 20 of the main discharge may bring about a considerable change in the starting potential required.

I have found that if the portion of the starting electrode which projects below the mercury surface be tapered in a manner which may be predetermined from the electrical characteristics 25 of the electrode body, the effect of mercury level variations on starting voltage will be nullified. For most of the practical electrode materials the required taper will take the form of a concave cone.

30 The novel features which I consider to be characteristic of my invention will be pointed out with particularity in the appended claims and may be fully understood upon reference to the following specification and drawing in which Fig. 1 is a partially diagrammatic illustration of the arrangement in which my improved electrode is to be employed; while Fig. 2 is a detailed view 35 partly in section of the starting electrode itself; Figs. 3, 4 and 5 are graphical representations of 40 various relationships which illustrate and explain the nature of my invention.

Referring more particularly to Fig. 1, I have 45 illustrated a mercury pool tube comprising an elongated sealed envelope 1 provided at each end 50 with stem portions 2 of reduced diameter. A tubular extension 3 is shown projecting laterally from one side of the envelope near its base.

In the lower portion of the envelope 1 is 55 collected a quantity of mercury 4 whose surface level is necessarily variable with the tilting or vibration of the tube, or with evaporation of mercury from the pool. The mercury may be connected to an external source of potential by means of a lead-in conductor 5 which is brought to the in-

terior of the envelope through a glass to metal seal 6.

At the top of the envelope is provided a positive electrode or anode 7, made of graphite, molybdenum or a corresponding heat-resisting 5 conducting material. This is shown suspended by means of a conductor 8 of high current capacity which is also provided with an external connection 9 suitably sealed to the envelope stem.

In contact with the mercury and projecting 10 below its surface, I have provided a starting electrode body 10 composed of a semi-conducting material such as tungsten or silicon carbide, suitably combined with clay or a similar binder. This is held in proper position by a depending 15 portion of a rigid conductor 11. This latter element is surrounded for a portion of its length by a glass tubulation 12 to protect it from condensation of mercury or graphite, and is taken out through a press 13 to make contact with a metallic 20 cap 14 mounted on the tubular extension 3.

Referring more particularly to Fig. 2, it will 25 be seen that the starting electrode body 10 is mounted in a suitable retainer 16 conductively fitted onto the electrode stem. The retainer in turn is welded or swaged into good contact with the supporting conductor 11. The starting electrode 10 is clearly shown as terminating at its 30 lower end in a concave conical surface of revolution. The downwardly convergent tip thus formed is positioned so that it projects partly above and partly below the level of the cathode pool during the normal operation of the discharge device.

For a more complete understanding of the 35 manner of operation of the tubes with which my invention is concerned, I have illustrated a typical circuit arrangement for such a tube. As shown, a conductor 17 is connected from one side of an alternating current source to lead-in 5, which as 40 above explained is in electrical contact with the mercury pool. The other side of the alternating current voltage supply is connected by conductor 18 to the anode in series with a load 19. The latter is illustrated conventionally as a 45 resistance but may consist of any type of intermittently operating mechanism such for example as a spot-welding device. A smoothing condenser 20 is shown shunting the direct current load 19 for the purpose of eliminating irregularities in 50 the current supply.

The starting electrode 10 is also connected to the anode terminal through a current-limiting resistor 22 and a unidirectional current-transmitting device 23. This is shown as a two-ele- 55

ment thermionic discharge tube, but may alternatively comprise an oxide film rectifier, or equivalent element, capable of passing current only when the mercury pool is at negative potential 5 with respect to the anode. The constants of the tube 1 and the starting circuit are such that when the alternating current potential has reached a limiting value in such a direction that the anode becomes the positive electrode, current 10 passing from the starting electrode 10 into the mercury pool will initiate a discharge. This is a phenomenon familiar to those skilled in the art and is described in an article by J. Slepian appearing in the Transactions of the A. I. E. E. 15 for 1933, vol. 52, page 693.

The magnitude of the current required to cause a discharge to take place is variable with several factors as will be hereinafter more fully explained. This variation is not in itself a matter 20 of critical importance, however, since a considerable change in starting current may usually be permitted without serious consequences.

The external potential required to give rise to a sufficient starting current, on the other hand, 25 must frequently be kept constant or within closely confined limits. This is true, for example, if the load device to be served by the main discharge is a spot welder, as suggested above. In such a case, it is extremely important that the 30 arc-discharge be initiated only when the alternating line potential, and consequently the starting potential, has reached some exactly predetermined positive value. Only in this way can the duration of the power impulse transmitted 35 through the welding contact be regulated accurately. A deviation from such constancy of operation will result in a weld which is defective because of the application of either too much or too little heat, as the case may be.

40 Because of its poorly conducting characteristic the electrode body 10 acts as a resistance element in series with the starting circuit, the value of which changes in dependence on the length remaining above the surface of the mercury. 45 Consequently, if starting electrodes of constant diameter are used, variations in the mercury level will correspondingly vary the starting potential required to send a given amount of current into the mercury pool. This effect is shown graphically by curve A of Fig. 3 which represents observed variations in external starting potential obtaining with a straight electrode as plotted against deviations in mercury level from an arbitrary normal line. Since fluctuations of this type 50 lead to irregularity in operation as above explained, it is highly desirable to provide means of eliminating them.

It has been found that the amount of starting current, as distinguished from voltage, required to initiate a discharge between the main electrodes of a mercury pool tube depends to a large extent on the diameter of the starting electrode at its line of contact with the mercury surface. I have observed experimentally that a decrease or increase in such diameter results in a corresponding decrease or increase in the amount of starting current needed. In Fig. 4 I have shown the nature of this relationship as determined for the electrode material used in obtaining the data plotted in Fig. 3. The curve B illustrates the variation of starting current with electrode diameter at the line of contact, other factors being held constant.

Because of this inherent quality of the mercury pool starter it is possible, and my invention

contemplates, that the tip of the starting electrode may be given a calculated form such that the effect of variations in mercury level on the starting voltage will automatically be compensated. In other words, an increase or decrease 5 in necessary starting current will be balanced by a corresponding change in series resistance so that the total voltage drop remains unchanged.

The nature of the electrode configuration required to accomplish this result will be a function not only of the starting current characteristic but also of the external circuit constants, and the specific resistance of the particular electrode body, but may be determined empirically for any given material. Alternatively, to the 10 extent that the relationship between starting current and contact diameter is capable of being expressed mathematically, the corresponding electrode contour which will result in constant voltage starting may be computed exactly by setting up and solving the equations defining the 15 desired conditions. For electrode substances within any practical range of specific resistivities the appropriate shape will be that of a concave conical surface of revolution as described 20 above.

As exemplary of the manner in which my invention is to be applied, I have shown in Fig. 5 a graphical outline of the shape determined as proper for the tip of an electrode having the 25 starting current characteristic shown in Fig. 4. The electrode is also chosen to have a specific resistivity equal to that of the test electrode used in connection with curve A of Fig. 3. By a comparison of Figs. 4 and 5 it will be seen that a rise 30 in the mercury level will so increase the electrode diameter at the line of contact that a greater starting current will be required. On the other hand, the series resistance of the electrode body 10 will necessarily diminish in accordance 35 with the change in the dimensions of the resistance path. These two effects will, under the conditions stated, offset one another so that the required starting potential will remain constant. 40 curve C of Fig. 3 illustrates this result and affords a comparison with the voltage-mercury level characteristic obtained with a straight electrode.

I have described my invention as being especially applicable to mercury pool tubes, but it 50 will be obvious that its utility extends to other liquid conductors such as gallium which are suitable for use as cathode materials.

The invention of a downwardly convergent discharge-initiating electrode is claimed broadly in 55 application, Serial No. 74,653, filed April 16, 1936, in the name of Hobart E. Rowe, and is not intended to be claimed herein except as improved by the use of a concave conical or equivalent form as disclosed in the foregoing. However, 60 while I have shown a particular embodiment of my invention, many modifications may be made without departing from the invention, and I aim in the appended claims to cover all such modifications as fall within the true spirit and scope 65 of the preceding disclosure.

What I claim as new and desire to secure by Letters Patent of the United States, is:

1. In an electric discharge device, an anode, a mercury cathode, and a starting electrode supported above said cathode and having a portion thereof depending into permanent contact with said mercury, said portion comprising a downwardly convergent body of semi-conducting material bounded by a concave conical surface of 75

revolution which projects partly above and partly below the mercury level.

2. In an electric discharge device, an anode, a pool-type cathode, a starting electrode supported above said cathode pool and having a tip portion depending into permanent contact therewith, and a conductor connected with said starting electrode for impressing a discharge-initiating potential thereon, the tip portion of said starting electrode comprising a semi-conducting body bounded by a downwardly convergent concave surface of revolution whereby variations in the line of contact of said pool with said body are prevented from substantially affecting the potential required to be impressed on said starting electrode to initiate a discharge.

3. In a discharge device, an anode, a pool-type cathode having a variable surface level, a discharge-initiating electrode of semi-conducting material supported above said pool and having a downwardly convergent tip projecting partly above and partly below the level of the pool during normal operation of the device, said electrode tip being so formed that a change in resistance of the starting current path due to variations in level of said pool will be compensated by a change in the diameter of the line of surface contact of said electrode with said pool whereby the potential required to be impressed on the electrode

to initiate a discharge is maintained substantially constant.

4. In a discharge device, an anode, a pool-type cathode having a variable surface level, a semi-conducting electrode having a downwardly convergent tip projecting below the surface of the pool during normal operation of the device, and means for impressing a starting potential on said electrode, said electrode tip being so formed that a change in starting current due to variations in the line of contact of said tip with said pool will be compensated by such a change in the dimensions of the current path that the required starting potential is maintained substantially constant.

5. In a discharge device, an anode, a pool-type cathode and a semi-conducting starting electrode having a downwardly convergent tip portion depending into permanent contact with the surface of said pool, the shape of said tip portion being so related to the specific resistance of the electrode material that variations in the line of contact of the pool with the electrode are prevented from appreciably affecting the potential required to be impressed on the starting electrode for initiating a discharge between said anode and cathode.
